UNITED STATES PATENT OFFICE.

WILLIAM A. WALES, OF NEWTON, ASSIGNOR TO THE AUBURNDALE WATCH COMPANY, OF WESTON, MASSACHUSETTS.

THERMOMETER.

SPECIFICATION forming part of Letters Patent No. 240,058, dated April 12, 1881.

Application filed November 6, 1880. (Model.)

To all whom it may concern:

Be it known that I, WILLIAM A. WALES, a citizen of the United States, residing at Newton, in the county of Middlesex, and in the State of Massachusetts, have invented a new and useful Thermometer, of which the following is a specification.

This invention relates to certain improvements in that class of instruments known as "mechanical thermometers," in which the changes of temperature are noted by means of a dial and pointer or index operated by the unequal expansion of strips of different metal.

This class of instruments are noted for their extreme delicacy and sensitiveness to the smallest changes in temperature, and the time required for registering a difference of many degrees is only a few seconds. This extreme susceptibility of the bimetallic strip, which operates the registering device, tends to produce a tremulous, unsteady, and unequal movement of the index-hand, the fluctuations caused by the varied expansion or contraction of such strip being multiplied by the long leverage 25 through which the motion is transmitted.

In devices of this class hitherto in use various methods have been employed to counteract this evil, such as the use of a hair-spring upon the pointer-shaft. None of these devices, so far as I am aware, have completely succeeded in accomplishing their purpose.

The object of my invention is to provide a regulating and governing device for causing a uniform movement of the index-hand, or for holding it when at rest perfectly stationary without fluctuation. These objects I attain by the apparatus and mechanism illustrated in the accompanying drawings, in which—

Figure 1 represents a view, in perspective, of the device complete; and Fig. 2, a view showing the mechanism detached.

The letter A indicates a casing, which may be constructed of metal, hard rubber, or other suitable material. The said case is preferably made cylindrical in shape, and is constructed in two parts, similar to a pocket-compass case, the said parts being separable, so as to place the works within convenient reach for cleaning or repair. The interior of the lower part 50 of the case is provided with lugs, pins, or other

supports for a dial, D, which is confined by means of suitable fastenings, E.

To the lower or rear face of the dial is secured metallic frame F, which carries the working parts of the device. To said frame, at one end, is secured a bridge, G, similar to the bridge forming one of the bearings of the journal of a watch escapement-wheel.

The letter H indicates the index or pointer shaft. This shaft is journaled in a central bearing in the frame F and in a bearing in the bridge, so as to be capable of rotating freely, and projects through the dial at its center, and has an index or finger, H', secured to it. The said shaft is provided with a pinion, I, with which two toothed segments, K L, engage. The segment L is journaled on an arbor, P, secured to the supporting-frame, and has a short extension, Q, provided with a series of apertures, whereby may be adjustably connected to it a small link, R. The said link connects with one end of the bimetallic strip S, which is curved, and fastened at its other end to the supporting-frame.

The regulating device consists of a cogged 75 segment, K, substantially like the segment L, already described, and pivoted at the point k, so that its teeth engage with the pinion I on the pointer-shaft. It thereby offers a certain amount of resistance to the movement of the 80 pinion, not sufficient to stop it, but enough to neutralize the minute fluctuations on the bimetallic strip, which, when magnified by the length of the pointer, are quite appreciable. A spring, O, bears on a pin near the end of 85 the segment, and by maintaining a constant pressure on such segment assists in giving steadiness and uniformity to its motion.

The case is provided on one or both sides with crystals, similar to watch-crystals, by 90 which the interior may be readily observed.

The operation of my invention is as follows: The metals composing the bimetallic strip expand and contract unequally under the influence of changes of temperature. This actuates the segment L, which operates the index-shaft, turning the index, and indicating the temperature on the dial, which is properly graduated on its face. The segment K is actuated by the hair-spring to return the index (and 100

keep it from slipping back) to its normal position, in addition to the force exerted upon it for the purpose by the bimetallic strip, thus insuring its complete return.

5 Having thus described my invention, what I claim, and desire to secure by Letters Patent, is—

In a thermometer, the combination of a bimetallic strip adjustably connected to the seg-

ment L, the pinion I on the pointer-shaft, and a governing device consisting of the pivoted cogged segment K, engaging with said pinion, and the spring O, substantially as and for the purposes set forth.

WILLIAM A. WALES.
